UNITED STATES PATENT OFFICE.

GEORG SCHMITT, OF NUERMBERG, GERMANY, ASSIGNOR TO WESTINGHOUSE ELECTRIC & MANUFACTURING COMPANY, A CORPORATION OF PENNSYLVANIA.

TILTABLE FURNACE.

Application filed February 16, 1927, Serial No. 168,591, and in Germany April 20, 1926.

My invention relates to melting furnaces and particularly to that type of furnace which is tiltable to discharge the molten material.

5 An object of my invention is to provide an electric furnace wherein the discharge of the molten material is facilitated.

Another object of my invention is to provide a tilting furnace that shall require a 10 relatively small amount of power to tilt the same.

In practicing my invention, I provide an 15 electric furnace of the resistor type mounted upon a supporting base for limited movement in a horizontal plane and tilting movement about a horizontal axis substantially coincident with its center of gravity. Upon the base, I further provide a substantially 20 vertical channel member which cooperates with a roller mounted upon the furnace casing to guide a portion of the periphery of said casing, preferably the discharge spout, in a vertical path when the furnace is tilted.

In the drawing, Fig. 1 is a view, in end 25 elevation, of a furnace embodying my invention;

Fig. 2 is a view, in side elevation, thereof;

Fig. 3 is a detailed view showing the construction of the guide roller; and

30 Fig. 4 is a section taken on the line IV—IV of Fig. 2.

In the drawing 10—11 designate vertically disposed supporting members spaced at their top and bottom by braces 12—13. These supports include substantially flat horizontal bearing surfaces 14 with abutments 15 at one end thereof, and vertically disposed channel members 16.

The furnace comprises a chamber 20 40 rounded by a resistor 18 and suitable refractory material 19, all contained within a casing 24. A discharge passage 22 extends from the chamber of the furnace through the refractory material and terminates in a discharge spout 26 on the periphery of the casing. A charging opening for the chamber 20 is indicated at 28 and is closed by a door 30 operable by means of levers 32, 33 and 34, and a counterweight 35. Upon the ends of 45 the casing and located on a horizontal line extending through the center of gravity thereof are trunnions 36 upon which are mounted rollers 38 provided with outer flanges 40.

50 The furnace is mounted between the sup-

ports 10—11 with the rollers 38 riding upon the flat bearing surfaces 14 and the flanges 40 engaging the sides thereof to maintain said furnace in proper relation to said supports, so that the furnace may be tilted about 60 said trunnions as an axis and may be moved in a horizontal plane.

Upon one end of the casing adjacent the periphery thereof and on a horizontal line extending through the discharge spout is a 65 lug 42, provided with an aperture in which a bolt 44 is rotatably received. A block 48 is provided with a threaded aperture to receive the threaded end of bolt 44, and is positioned within the channel 16. Upon bolt 70 44 adjacent to block 48 is mounted a roller 46 rotatable with respect to block 48 and bolt 44, and of a suitable diameter to be positioned between the flanges of the channels 16 and engage the sides of the same, all of 75 which is shown more particularly in Figs. 3 and 4.

The tilting mechanism comprises a chain 54, the ends of which are secured to block 48 and the intermediate portion extends over 80 a plurality of guide rollers 56, rotatably mounted upon the support 10, and a toothed wheel 52. Wheel 52 is also rotatably mounted upon the supports 10 and is actuated by a 85 crank arm 50 whereby movement of said crank arm rotates wheel 52 which actuates chain 54 to move block 48 along the guide 16.

In operation, when the melting is complete, crank 50 is turned in a clockwise direction 90 which actuates the toothed wheel 52 and chain 54 to move block 48 downwardly. The 95 downward movement of block 48 and roller 46 mounted therewith is guided by the channel 16 in a vertical path and, since the block and roller are secured to the furnace casing 100 adjacent the periphery thereof, the furnace is tilted about the trunnions 36 and moved horizontally a limited distance along the surface 14. The discharge spout being on a horizontal line through rollers 46, is, therefore, moved downwardly along a vertical path to discharging position. The horizontal movement of the rollers 38 along the surface 14 is initially towards the right and then towards the left (as seen in Fig. 1) and the 105 limit of turning movement of the furnace is reached when the rollers 38 engage the vertical portions 15 of the supports 10, 11.

The vertical guiding of the spout has the result that the molten metal will leave it in 110

substantially the same direction in all of the tilted positions of the furnace whereby any movement of the crucible receiving the molten metal becomes unnecessary.

5 It will be further noted that, with the furnace mounted for tilting on a line extending substantially through the center of gravity and with the tilting force applied to the periphery of the furnace, only a comparatively 10 small force is required to move the furnace to its discharging position.

Various modifications may be made in the device embodying my invention without departing from the spirit and scope thereof and 15 I desire, therefore, that only such limitations shall be placed thereon as are imposed by the prior art or are specifically set forth in the appended claims.

I claim as my invention:

20 1. In a tiltable furnace, a base comprising spaced vertical members, a horizontally disposed bearing surface and a vertically disposed guiding surface formed on each of

said members, a cylindrical furnace casing disposed between said spaced members, means carried by said casing on a horizontal line extending through the center of gravity thereof for supporting said casing upon said horizontally disposed bearing surfaces, means carried by said casing for engagement with said guiding surfaces, and means for tilting said casing about the center of gravity thereof.

2. A melting furnace comprising a furnace casing, a support for said casing permitting the rotation and lateral movement thereof, a pouring spout mounted upon said casing, and means for moving said spout in a vertical path upon rotation of said furnace comprising a stationary vertical guide and means mounted on said casing operatively associated with said guide.

In testimony whereof, I have hereunto subscribed my name January 8, 1927.

GEORG SCHMITT.
